UNITED STATES PATENT OFFICE.

FRANCISCO RIVED, OF ZARAGOZA, SPAIN.

REGISTERING PHOTOTACHYMETR.

Application filed June 11, 1921. Serial No. 476,958.

To all whom it may concern:

Be it known that I, FRANCISCO RIVED, engineer, subject of the King of Spain, residing at Zaragoza, Spain, have invented certain new and useful Improvements in Registering Phototachymeters, of which the following is a specification.

When working with any one of the tachymeters of the types hitherto known, the serious difficulty is encountered that, in taking note of the data obtained with the apparatus, an error may easily occur and false particulars be registered.

My apparatus avoids this drawback and by way of example and in its essential parts I will represent it in the accompanying drawings, in which:

Fig. 1 is a section of the whole apparatus;

Fig. 2 is a horizontal projection of the interior of the indicator;

Fig. 3 is a projective view of the rear part of the photographic camera, and

Fig. 4 is a representation of the aspect of the photograph in which the data are photographed or registered.

Description of the apparatus.

The apparatus consists essentially, Fig. 1, of a vertical rotary shaft $-e-$ provided with a platform with levelling screws according to any of the systems used in topographical apparatus and of a pressure screw $-p-$ and of another coincidence screw $-c-$ so as to be able to obtain the movements desired, either rapid or slow, as in the usual tachymeters.

Irreversibly attached to the vertical rotary shaft is the small plate $-P-$ and upon it are one or more air levels or the like, which are not shown in the figure, so as to determine the horizontal position of the small plate.

Two uprights $-m-$ and $-m'$ —, or other similar devices, serve as a support for the following elements:

There is a tele-objective $-T-$ with a horizontal rotary shaft and spindle $-E-$ perpendicular to its optical axis. Opposite the opening of the said axis or shaft there is a total reflecting prism $-P'$ — the two cathetic faces of which are respectively perpendicular to the optical axis or shaft of the tele-objective and to the horizontal turning axis. This axis is supported on the two uprights or the like $-m-$ and $-m'$ — and is provided with a pressure screw and another

for coincidence, which are not shown in the figure and which may be of any one of the systems used in the topographical apparatus and the object of which is to obtain the rapid and slow turning movements of the tele-objective. The said tele-objective will be provided with a sight which may be an eyepiece, with alidades or with any other system and which will be placed above the tele-objective or laterally.

In the upper part of the uprights or the like $-m-$ and $-m'$ — there is located the box $-C-$ for the indicator or compass, closed at its upper portion by a ground glass $-c'$ — and at its lower part by a transparent glass $-c''-$. The magnetic needle $-M-$ is mounted on the transparent glass $-c''-$ and carries in its axis and in the whole of its thickness a saw cut $-S-$ (Fig. 2) provided in one of its sides with a boring $-t-$ or any other sign which serves to distinguish the north point from the south. The plane of the compass box is parallel to that of the plate $-P-$.

In the upright or the like (Fig. 1) there is an object glass $-o-$ with a mounting provided with a total reflecting prism $-P''-$ — the two cathetic faces of which are respectively perpendicular to the optical axis of the object glass $-o-$ and to the vertical turning axis of the apparatus.

Not only the prism $-P''-$ — but also $-P'$ — may be replaced by mirrors the planes of which occupy the positions of the hypothenuse faces of the prisms.

Upon the upright or the like $-m-$ (Fig. 1) there is mounted a camera obscura $-C'$ — divided by a divisory partition $-D-$ (similar to those used in the chambers of stereoscopes), with a small curtain obturator $-o'$ — and with a chassis or frame for the film $-Ch-$ or with various frames for plates. This camera is so adjusted that the plane, in which the images proportioned by the object glass $-o-$ and the tele-objective $-T-$ are formed, may be vertical when the small plate $-P-$ is horizontal.

The camera obscura carries in its rear part (Fig. 3) an opaque screen $-o''-$ — the plane of which is parallel to that of the film or sensitized surface and very close to this latter and which only leaves uncovered two small circles $-A-$ and $-A'$ — each of which bears two notches or incisions $-n-$ and $-n'$ — and $-l-$ and $-l'$ — at the extremities of their vertical diameters or in any

other suitable position so that they determine verifying lines of known position.

It is unnecessary to say that the characteristics of the apparatus will be calculated in suchwise that the images supplied by the object-glass —*o*— and the tele-objective —*T*— will be formed on the same plane, which will be that of the sensitized surface.

10   Method of operation of the apparatus.

In order to work with this apparatus, we shall utilize, just as with any current tachymeter, a graduated sight carrier which will maintain the device adjusted or "set" to 15 those points of the land, details of which it is desired to obtain. This being determined, we will come to the workings of the various parts of our photo-tachymeter.

The three data it is desired to obtain are, 20 as with all other tachymeters: the horizontal angle or azimuth, the vertical angle or zenith, and the inclined distance.

Horizontal angle.—As the lower part of the compass box is a transparent glass 25 —*c''*— and the upper part of ground glass —*c'*— (Fig. 1), the image of the magnetic needle —*M*— reflected in the prism —*P''*— and formed by the object-glass —*o*— will be 30 formed in the sensitized film and the light passing through the saw out —*S*— (Fig. 2) of the magnetic needle and of the boring —*t*— will give us upon the sensitized surface an image similar to —*I*— (Fig. 4).

If we cause the apparatus to turn round 35 its vertical axis, as the magnetic needle remains always fixed marking the direction of the magnetic meridian, the relative position of the needle with relation to the plane of the sensitized surface will be distinct 40 for the distinct positions and the image of the needle will form distinct angles with the verifying line determined by the notches —*n*— and —*n'*— of Figure 3. The angle formed by the image of the axis 45 of the needle with the line of the notches is the horizontal or azimuthal angle.

Vertical angle.—The longitudinal axis of the prism —*P'*— (Fig. 1) being perpendicular to the optic angle of the tele-objective 50 —*T*—, it will be clear that the image of the sight upon the sensitized surface will be vertical when the optical axis of the tele-objective is horizontal. When the optical axis of the tele-objective forms a certain ascendant 55 or descendant angle with the horizontal, the image of the sight will form the same angle with the line determined by the notches —*l*— and —*l'*— of Fig. 3 and to its right or to its left, according as the inclination 60 of the tele-objective may be ascendant or descendant. The image will have an aspect similar to that of —*I'*— (Fig. 4).

Inclined distance.—It will be evident that 65 for one and the same tele-objective the size of the image of the sight registered in the

sensitized film is invariably in proportion to the distance of the apparatus in relation to the sight, and the distance will be determined by the size of the image of the sight.

In Fig. 4 there may be seen the aspect of 70 the sensitized surface upon which there are photographed the three details required for the tachymetric preparation of plans and the measuring of altitudes.

75   Use of the apparatus.

It is placed upon a tripod just the same as any other tachymeter, but with the essential difference that it will not be necessary to effect coincidences of the zeros of the 80 limb and nonius, because without effecting this operation or guiding it, the guiding or orientation will register itself automatically in the photograph of the magnetic needle. It will then be sufficient to adjust the sight 85 and release the obturator in order that the necessary data may remain printed on the sensitized surface. When this is once developed or revealed by the ordinary photographic processes we shall be in possession 90 of the details which we require.

Appreciation of the data.

Taking into account the small magnitude of the images obtained, it will be seen that 95 it will be necessary, in order to appreciate or value the data, to amplify the images by projection to a certain number of increases. In order to value the angles we will make use of a simple arrangement 100 which consists of a small plate with a graduated circumference, upon the plane of which there will be projected, as upon a screen, the images obtained on the sensitized surface. In the plane of said circumference 105 there will be marked signs which determine directions homologous to those determined by the notches —*n*— —*n'*— and —*l*—, —*l'*— of Fig. 3. By endowing the graduated circumference with a nonius or the like we shall 110 be able to appreciate or value the angles with as much approximation as may be desired.

As regards the valuation of the distance it will suffice to measure by suitable means 115 the dimension of the divisions of the sight projected upon the screen, and it is evident that, knowing the dimension of the divisions of the sight, the equivalent focus of the tele-objective and the number of lineal increases to which we have amplified the image by projection, we shall know the distance at which the apparatus was from the sight at the moment of photographing the same.

Having described my invention I claim: 125

1. In a registering photo-tachymeter, a supporting frame, means for supporting the frame for rotation about a vertical axis, a tele-objective carried by said frame for rotation about a horizontal axis, a compass 130

- needle pivotally carried in a horizontal position by the frame, means carried by the frame for projecting an image of the compass needle position in a direction parallel to the image forming rays projected from the tele-objective, and a photographic camera containing a sensitized film carried by the frame in a position to photographically record the image of the compass and 5 the image projected by the tele-objective, when in any relative positions.
2. In a registering photo-tachymeter, a supporting frame, means for supporting the frame for rotation about a vertical axis, 10 a tele-objective carried by said frame for rotation about a horizontal axis, a compass needle pivotally carried in a horizontal position by the frame, means carried by the frame for projecting an image of the compass 15 needle position in a direction parallel to the image forming rays projected from the tele-objective, and a photographic camera containing a sensitized film carried by the frame in a position to photographically 20 record the image of the compass and the image projected by the tele-objective when in any relative positions, said camera having therein a screen with reference marks thereon which are photographed upon the 25 film simultaneously with the images for reference in measuring the angles of the images from known reference lines.
3. In a registering photo-tachymeter, a supporting frame, means for supporting the frame for rotation about a vertical axis, a tele-objective carried by said frame for rotation about a horizontal axis, a compass needle pivotally carried in a horizontal position by the frame, means carried by the 30 frame, for projecting an image of the compass needle position in a direction parallel to the image forming rays projected from the tele-objective, and a photographic camera containing a sensitized film carried by 35 the frame in a position to photographically record the image of the compass and the image projected by the tele-objective when in any relative positions, said camera having therein a partition for preventing confusion 40 of the luminous rays forming the two images.
4. In a registering photo-tachymeter, a tele-objective, a compass needle, a frame for supporting the needle for rotation about a vertical axis and the tele-objective for rotation about a horizontal axis, means for supporting the frame for rotation about a vertical axis, means for projecting an image of the compass needle position, and means 45 for photographically recording the images from the tele-objective and the said projecting means.
5. In a registering photo-tachymeter, a tele-objective, a compass needle, a frame for supporting the needle for rotation about a vertical axis and the tele-objective for rotation about a horizontal axis, means for supporting the frame for rotation about a vertical axis, means for projecting an image of the compass needle position, and means for photographically recording upon the same film the images from the tele-objective and the said projecting means.
6. In a registering photo-tachymeter, a tele-objective a compass needle, a frame for supporting the needle for rotation about a vertical axis and the tele-objective for rotation about a horizontal axis, means for supporting the frame for rotation about a vertical axis, means for projecting an image of the compass needle position, and means for photographically recording upon the same film the images from the tele-objective and the said projecting means.
7. In a registering photo-tachymeter, a tele-objective, a compass needle, a frame for supporting the needle for rotation about a vertical axis and the tele-objective for rotation about a horizontal axis, means for supporting the frame for rotation about a vertical axis, means for projecting an image of the compass needle position, and a photographic camera carried by the frame and supporting a sensitized film in a position to receive and photographically record the images from the tele-objective and said projecting means.
8. In a registering photo-tachymeter, a tele-objective, a compass needle, a frame for supporting the needle for rotation about a vertical axis and the tele-objective for rotation about a horizontal axis, means for supporting the frame for rotation about a vertical axis, means for projecting an image of the compass needle position, and a photographic camera carried by the frame and supporting a sensitized film in a position to receive and photographically record the images from the tele-objective and said projecting means, said camera having therein a partition to prevent confusion of the luminous rays forming the separate images.
9. In a registering photo-tachymeter, a tele-objective, a compass needle, a frame for supporting the needle for rotation about a vertical axis and the tele-objective for rotation about a horizontal axis, means for supporting the frame for rotation about a vertical axis, means for projecting an image of the compass needle position, and a photographic camera carried by the frame and supporting a sensitized film in a position to receive and photographically record the images from the tele-objective and said projecting means, said camera having shutter devices for causing the recordation of the images to take place at any desired instant.
10. In a registering photo-tachymeter, a tele-objective, a compass needle, a frame for supporting the needle for rotation about a vertical axis and the tele-objective for rotation about a horizontal axis, means for supporting the frame for rotation about a vertical axis, means for projecting an image of the compass needle position, means for photographically recording the images from the tele-objective, and the said projecting means, and means for photographing measuring reference marks upon the film simultaneously with the images.

- frame, means for supporting the frame for rotation about a vertical axis, a compass needle carried by the frame for rotation about a vertical axis, a ground glass supported on the frame above said needle, a camera carried at one side of the frame and having a sensitized photographic recording surface, a total reflecting prism supported beneath the needle for projecting the vertical rays of light from the needle in a horizontal direction, and means for forming the horizontally projected rays into an image of the needle upon the said recording surface.
11. In a registering photo-tachymeter, a frame, means for supporting the frame for rotation about a vertical axis, a compass needle carried by the frame for rotation about a vertical axis, a ground glass supported on the frame above said needle, a camera carried at one side of the frame and having a sensitized photographic recording surface, a total reflecting prism supported beneath the needle for projecting the vertical rays of light from the needle in a horizontal direction, means for forming the horizontally projected rays into an image of the needle upon the said recording surface, a tele-objective carried by the frame for rotation about a horizontal axis, said tele-objective having a ray receiving barrel extending radially to the horizontal axis of its rotation and a reflecting prism at the juncture of the radial and horizontal sections of the same for projecting the image forming rays through the horizontal section upon the recording surface of the camera.
12. In a registering photo-tachymeter, a frame, means for supporting the frame for rotation about a vertical axis, a compass needle carried by the frame for rotation about a vertical axis, a ground glass supported on the frame above said needle, a camera carried at one side of the frame and having a sensitized photographic recording surface, a total reflecting prism supported beneath the needle for projecting the vertical rays of light from the needle in a horizontal direction, means for forming the horizontally projected rays into an image of the needle upon the said recording surface, a tele-objective carried by the frame for rotation about a horizontal axis, said tele-objective having a ray receiving barrel extending radially to the horizontal axis of its rotation and a reflecting prism at the juncture of the radial and horizontal sections of the same for projecting the image forming rays through the horizontal section upon the recording surface of the camera, said camera having a partition wall to prevent confusion of the rays forming the two images.
13. In a registering photo-tachymeter, a frame, means for supporting the frame for rotation about a vertical axis, a tele-objective carried by the frame for rotation about a horizontal axis, said tele-objective having a portion of its barrel along the horizontal axis of rotation and the objective end at right angles to the horizontal axis whereby luminous rays from the objects within the range of the tele-objective during rotation of the objective end in a vertical plane will be projected through the horizontal portion, and means for photographically recording the image formed by the rays from the tele-objective projected through the horizontal portion.
14. In a registering photo-tachymeter, a frame, means for supporting the frame for rotation about a vertical axis, a tele-objective carried by the frame for rotation about a horizontal axis, said tele-objective having a portion of its barrel along the horizontal axis of rotation and the objective end at right angles to the horizontal axis whereby luminous rays from the objects within the range of the tele-objective during rotation of the objective end in a vertical plane will be projected through the horizontal portion, and a camera carried by the frame and having a sensitized recording surface upon which the luminous rays from the tele-objective are focused as images during rotation of the tele-objective, said camera having a shutter for exposing the sensitized surface to the image at any instant.
15. In a registering photo-tachymeter, a frame, means for supporting the frame for rotation about a vertical axis, a tele-objective carried by the frame for rotation about a horizontal axis, said tele-objective having a portion of its barrel along the horizontal axis of rotation and the objective end at right angles to the horizontal axis, whereby luminous rays from the objects within the range of the tele-objective during rotation of the objective end in a vertical plane will be projected through the horizontal portion, and a camera carried by the frame and having a sensitized recording surface upon which the luminous rays from the tele-objective are focused as images during rotation of the tele-objective, said camera having a device for printing measuring reference marks simultaneously with the printing of the image.

In testimony whereof I affix my signature.
FRANCISCO RIVED.
